UNITED STATES PATENT OFFICE.

CASSIUS M. COLLINS, OF BAKERSFIELD, CALIFORNIA.

INCLINOMETER.

Application filed April 1, 1926. Serial No 99,099:

The invention relates to instruments adapted for use upon aerial, submarine or land vehicles to determine the inclination at which the craft or vehicle is standing at any desired time, and it is the object of such invention to provide a device of this character which is of simple and inexpensive construction, yet is highly efficient and desirable and can by no possibility get out of order unless seriously injured by some accident.

With the foregoing in view, the invention resides in the novel subject matter herein-after described and claimed, the description being supplemented by the drawing.

Figure 1 is an elevation of an inclinometer constructed in accordance with my invention, showing it mounted upon a vertical support, such as an instrument board.

Figure 2 is a side elevation of the device mounted upon the support.

Figure 3 is a top plan view of the inclinometer, showing the support in horizontal section.

Figure 4 is a vertical sectional view on line 4—4 of Fig. 1.

Figure 5 is a view similar to Fig. 4 but showing the support disposed at an inclined position instead of vertically as in the other views.

In the drawing above briefly described, the numeral 6 designates a face plate adapted to be secured by screws or the like 7 to an instrument board or other support 8, said face plate having a forwardly bowed portion 9 shaped to correspond to a section of a cylinder, this bowed portion being formed with a view opening 10 across which an indicator 11 is secured. This indicator may well be formed from a length of wire having its end soldered or otherwise secured in place.

A U shape yoke 12 is shown having its ends bent laterally outward at 13 and secured by rivets or the like 14 to the rear side of the face plate 6, said yoke being disposed in a plane at right angles to the plane in which the body portion of said face plate is located. Passing rotatably through openings in the arms of this yoke, is a shaft 15 which is concentric with the bowed portion 9 of the face plate 6, said shaft preferably having collars 16 disposed at the outer sides of said yoke arms, to hold the shaft against axial shifting. Secured upon the shaft to rotate bodily with it is a wheel 17 which preferably comprises end plates 18 and the cylindrical side wall

19, the periphery of this wheel being disposed at the rear face of the forwardly bowed plate portion 9, so as to be readily visible through the opening 10. The wheel is provided with a weight 20 which is preferably located within it as shown, said weight being spaced from the shaft 15 and secured suitably to the wheel, so that said wheel will be held against rotation, regardless of the angle to which the face plate 6 and the support 8 turn with respect to said wheel. The periphery of this wheel is divided into degrees and its graduations are read in connection with the indicator 11, so that by merely glancing at this indicator and the degree designation 70 behind it, the inclination of the airship, submarine, land vehicle or the like with respect to the horizontal, may readily be ascertained.

The device is of extreme simplicity and can by no possibility get out of operative condition unless accidentally injured, and it will be efficient and in every way desirable. On account of the excellent results obtainable from the details disclosed, they are by preference followed. It will be understood, 80 however, that within the scope of the invention as claimed, numerous minor variations may be made.

I claim:

An inclinometer comprising a face plate 85 having a forwardly bowed portion shaped to correspond to a section of a cylinder and formed with a view opening, an indicator spanning said opening, a yoke of substantially U-shaped form disposed behind said face plate and having its ends bent laterally and secured to said face plate, said yoke being disposed in a plane at right angles to the plane of said face plate and having in its arms bearing openings, a wheel disposed 90 between the arms of said yoke and having a shaft the ends of which engage and project through the bearing openings in the arms of the yoke, collars fixed on the projecting ends of said shaft, said wheel having its peripheral portion disposed at and close to the rear side of the forwardly bowed portion of said face plate, said peripheral portion of the wheel being provided with degree designations, and a weight arranged eccentrically 95 on said wheel.

In testimony whereof I have hereunto affixed my signature.

CASSIUS M. COLLINS.
